(57) **CLAIM**

The ornamental design for a case for a breast prosthesis, as shown and described.

DESCRIPTION

FIG. 1 is a perspective view of a case for a breast prosthesis showing our new design;

FIG. 2 is a side elevational view of the case for a breast prosthesis illustrated in FIG. 1;

FIG. 3 is a bottom plan view of the case for a breast prosthesis illustrated in FIGS. 1 and 2;

FIG. 4 is a top plan view of the case for a breast prosthesis illustrated in FIGS. 1-3; and,

FIG. 5 is an end elevational view of the case for a breast prosthesis illustrated in FIGS. 1-4, the other end elevational view being a mirror image.
